(57) **CLAIM**

The ornamental design for a tray for transporting and storing electronic components, as shown and described.

DESCRIPTION

FIG. 1 is a top perspective view of the tray for transporting and storing electronic components;

FIG. 2 is a bottom perspective view of the tray for transporting and storing electronic components of FIG. 1;

FIG. 3 is a top plan view of the tray for transporting and storing electronic components of FIG. 1;

FIG. 4 is a bottom plan view of the tray for transporting and storing electronic components of FIG. 1;

FIG. 5 is a left side elevational view of the tray for transporting and storing electronic components of FIG. 1;

FIG. 6 is a right side elevational view of the tray for transporting and storing electronic components of FIG. 1;

FIG. 7 is a front elevational view of the tray for transporting and storing electronic components of FIG. 1;

FIG. 8 is a rear elevational view of the tray for transporting and storing electronic components of FIG. 1;

FIG. 9 is a cross-sectional view taken through the line 9-9 in FIG. 3; and,

FIG. 10 is a cross-sectional view taken through the line 10-10 in FIG. 3.

The broken lines in the drawings illustrate portions of the tray for transporting and storing electronic components that form no part of the claimed design.

1 Claim, 10 Drawing Sheets
